UNITED STATES PATENT OFFICE.

EDWIN FELIX, OF CHICAGO, ILLINOIS.

EXTENSIBLE TOOL.

1,412,235.

Specification of Letters Patent. Patented Apr. 11, 1922.

Application filed September 3, 1921. Serial No. 498,503.

To all whom it may concern:

Be it known that I, EDWIN FELIX, a citizen of the United States, residing at Chicago, in the county of Cook and State 5 of Illinois, have invented certain new and useful Improvements in an Extensible Tool, of which the following is a specification.

This invention relates to certain new and useful improvements in an extensible tool or 10 device, and it consists in certain peculiarities of the construction, and in the novel arrangement and combination of the various parts thereof.

The principal object of my invention is 15 to provide an extensible tool or handle, to be used in connection with tap or socket wrenches, or other rotatable tools, when it is desired to use them for doing their work in places where they can not be used on 20 account of the almost inaccessible position of the parts to be engaged by the wrenches and the like; which shall be extremely simple and inexpensive in construction, strong, durable, efficient in operation, with its parts 25 so made, arranged and co-operating with one another, that the device can be readily attached to a tap or socket wrench or other desirable tool, and its parts quickly and easily extended to a suitable length and then 30 securely locked in their adjusted position.

Other objects and advantages of the invention will be disclosed in the following description and explanation.

In the accompanying drawing, which 35 serves to illustrate an embodiment of the invention—

Fig. 1 is a longitudinal sectional view of a tool embodying my improvements.

Fig. 2 is an enlarged detached perspective 40 view of a key used in connection with the members of the device, and

Fig. 3 is a cross-sectional view taken on line 3—3 of Fig. 1 looking in the direction indicated by the arrows.

45 Referring now more particularly to Fig. 1 of the drawing, the reference numeral 5 designates the body of the tool which may be made of any suitable size, form and material, but preferably cylindrical in shape 50 and of metal. One end of the body 5 is provided with a screw-threaded reduced portion 6 for insertion into a suitable socket of a wrench or its handle, and near the reduced screw-threaded portion, said end of 55 the body is provided with a cross-sectionally angular portion 7 by means of which a

wrench or clamping device may be applied for turning the body and the wrench or tool after the latter has been secured to or mounted on the part 6 of the body. The 60 opposite end of the body 5 is provided with external screw-threads 8 to engage internal screw-threads on a sleeve 9, which is rotatably mounted on the body 5. That end of the body 5 carrying the screw-threads 8 65 is provided within its bore or cavity with a longitudinally extended and inwardly inclined key-way 10 for the reception of a locking key 11 which may be made of any suitable size and form, yet by preference of 70 about the shape shown in Fig. 2 of the drawing.

The outer end of the sleeve has an inwardly extended annular flange 12 to engage a transversely disposed groove 13 with 75 which the key 11 is provided on its outer surface near its outer end. This key has its outer surface beveled or inwardly inclined to correspond with the inclination of the key seat 10 and has its opposite or 80 inner surface flat to rest on a flat portion 14 with which the extensible rod 15 is provided from its inner end to a point near its outer end. The outer end of the slideable rod 15 is by preference provided with a 85 cross-sectionally angular portion 16 to engage a wrench or other device for turning the tool after the parts thereof have been adjusted and locked in their adjusted positions. 90

From the foregoing, and by reference to the drawing, it will be readily understood and clearly seen that by my improvements I have provided an extensible device of the character described, which can be manufactured and placed on the market at a much less cost than any device for a similar purpose that I am aware of, without in any way diminishing its efficiency, durability 95 or strength. 100

The operation of the device is simple and as follows—

A tap or socket wrench or other suitable tool to be turned, may be mounted on the reduced portion 6 of the body of the tool, 105 when by screwing the sleeve 9 outwardly on said body, the key 11 will be retracted from its seat by reason of the action of the screw-threads of the sleeve with those on the outer end of the body of the device. As soon as 110 the key has become sufficiently loosened, it is manifest that the rod 15 can be moved

longitudinally with respect to the body so as to lengthen or shorten the tool.

When the parts have been adjusted to the desired position, the sleeve 9 can be turned

- 5 in the proper direction to cause the key 11 to advance in the key seat 10 until it reaches its inward limit, when it is obvious that the extensible rod 15 will be locked in position against rotary movement as well as longitudinal movement.

Having thus fully described my invention, what I claim as new and desire to secure by Letters Patent is—

1. An extensible tool comprising a tubular body having at one of its ends external screw-threads and at its other end means to engage a wrench or other device to be operated by the tool, a sleeve rotatably mounted on the body in screw-thread engagement therewith and having at its outer end an inwardly extended annular flange, a rod mounted in the body for longitudinal movement and having a portion of its surface flattened, and an inwardly tapered key interposed between said flattened portion of the rod and the inner wall of the body for slidable movement with respect to said parts, said key having at its outer end a transversely disposed groove engaging said flange on the sleeve.
- 15
- 20

ment with respect to said parts, said key 25 having at its outer end a transversely disposed groove engaging said flange on the sleeve.

2. An extensible tool comprising a tubular body having at one of its ends external 30 screw-threads and internally thereof an inwardly inclined key seat, said body having at its other end means to engage a wrench or other device to be operated by the tool, a sleeve rotatably mounted on the body in 35 screw-threaded engagement therewith and having at its outer end an inwardly extended annular flange, a rod mounted in the body for longitudinal movement and having a portion of its surface flattened, and an 40 inwardly tapered key interposed between said flattened portion of the rod and the inner wall of the body for slidable movement with respect to said parts, said key having at its outer end a transversely disposed groove engaging said flange on the sleeve.

EDWIN FELIX.
